UNITED STATES PATENT OFFICE.

EDGAR EARLE LITTLEFIELD, OF SEATTLE, WASHINGTON.

METHOD OF INTERMITTENTLY OPERATING APPARATUS.

1,404,155.

Specification of Letters Patent. Patented Jan. 17, 1922.

Application filed July 19, 1916. Serial No. 110,053.

To all whom it may concern:

Be it known that I, EDGAR EARLE LITTLEFIELD, a citizen of the United States, and resident of Seattle, county of King, and State of Washington, have invented certain new and useful Improvements in Methods of Intermittently Operating Apparatus, of which the following is a specification.

My invention relates to a method of intermittently operating apparatus through the medium of changes in the electrical condition of a circuit caused by variations in the character, or condition, of a fluid which forms a link in said circuit.

15 The object of my invention is to provide a method whereby an electric current may be automatically produced, or varied in intensity, or character, and this produced current, or the variation or modification of an 20 existing current applied to the operation of motor mechanisms.

My invention comprises certain steps, arranged and applied in a certain order and manner which will secure the desired results in the manner herein set forth and then defined in the claims terminating this specification.

In the accompanying drawings I have shown typical forms of apparatus which 30 may be employed to carry out my invention.

Figure 1 is a vertical section through a urinal having my invention applied thereto in one type of construction.

Figure 2 is a like view showing another 35 type of construction.

Figure 3 is a sectional elevation of a closet bowl having my invention applied thereto.

Figure 4 shows the manner in which my apparatus may be applied to a trap of a 40 flushing apparatus.

Figure 5 is a longitudinal section through a plug-like member which may be used as a terminal connection for the apparatus employed.

45 My method is particularly applicable in controlling the supply, or discharge of fluids which vary or are varied in electrical conductivity and electrolytic activity. Means suited to carrying out my invention are 50 shown in the drawings above referred to.

I have employed my method for the automatic flushing of such waste receptacles as urinals and water closets and find that the body wastes may be used either as the active 55 agent in an electro generative fluid or elec-

trolyte to complete a voltaic cell or to vary the resistance in the external path of a circuit. In other forms of apparatus employing my method the fluid may also form a resistance varied in resistance by the presence or absence of the body wastes either in the external or internal path of a circuit. Either an alternating or direct current may be used as the nature of the case may require. The circuit controlling the operating mechanisms may be either grounded or the current may be returned through an unearthed circuit.

Urine is known to be a very good electrolyte while the water normally forming the seal of such receptacles as urinals and water closets is a nonconductor, or, at least, a very poor one. By adding urine, fecal matter, or other body waste to this seal an electrolyte is produced capable of acting upon electrodes placed in the seal to thereby produce a current of appreciable amount. It will also so increase the conductivity of the fluid that the current passing therethrough is sufficient to control, or operate, other forces or mechanisms. If the fluid forming the seal of such vessels be considered as an electrolytic cell and electrodes be placed to contact therewith the varying resistance of the fluid, caused by the alternate addition of the waste and the flushing of the same, will so vary the current flow that this variation may be used to control the flushing operation. It is evident that practically any other apparatus might be operated in an analogous manner.

In Figure 1 is shown in section one form of apparatus, employing my method, wherein the waste is used to vary the resistance in the external path of a circuit 25, the current of which may be supplied, either by the batteries 6, or from any other suitable or convenient source, such as a dynamo. Either a direct or alternating current may be used, although I have found that in some forms 100 of apparatus, one type of current offers advantages over the other, as will appear hereinafter.

The electrically-operated valve 4 controls a supply of water from any convenient 105 source 3 for flushing the apparatus. Inserted in the trap 26 is a terminal or electrode 9, which may be constructed as in Figure 5, this resembling an ordinary spark plug, except that no spark gap is provided 110

and the insulating member 27 forms a tube within which is closely fitted the cylindrical carbon electrode 7. For this carbon electrode may be substituted any other acid-resistant conductor, such as either of the metals platinum or tungsten. The terminal 28 completes the circuit through the waste pipe 10. The current may be either grounded through the piping system or returned to its source in a manner similar to that shown. Where a nonconductive type of trap, such as earthenware, is used, companion electrodes may be placed to contact with the seal and the current either grounded or returned to its source as above indicated.

In operation the trap 26 normally contains water, which, in a pure state is non-conductive, but which has its resistance lowered by the addition thereto of a body waste, such as urine or fecal matter. Upon the addition of such waste, the conductivity of the trap fluid will increase to such an extent as to be capable of actuating the valve 4, thereby bringing about a flushing of the apparatus. When the flushing water has cleansed the trap, the resistance is thereby increased to cut down the current flow, thereby permitting the normally acting means to automatically close the valve.

While pure water is a nonconductor it would not always be convenient to use it for flushing purposes and as ordinary tap water sometimes carries impurities which vary its resistance, I have employed various means for preventing leakage of current where impure water is used. This result may be brought about, either by varying the immersed surfaces of the electrodes, or their distance apart, or both, or by allowing the gas formed by the chemical reaction to be deposited upon the electrodes.

Where an alternating current is used, however, certain advantages appear which make its use desirable in certain forms of apparatus. This is particularly due to the fact that less chemical reaction takes place in an alternating circuit and the heating effect is less than in a direct circuit.

Where the flushing fluid is slightly impure, or when, for any reason, it is desirable to automatically open the circuit, the gas formed by the chemical reaction of the current may be interposed as a resistance between the terminals.

In Figure 5, I have shown a modified form of electrode and have also shown the shell of the part 9, as partly broken away. The lower free end 8 of this electrode 7 is provided with a concave surface upon which the gas of polarization is deposited. In any apparatus employing my method, I contemplate that any suitable form of electrode, or its associated parts, may be used, whether specifically set out herein or not. It is evident that when sufficient gas has been de-

posited to cover this surface, the circuit will be automatically opened. It is likewise clear that upon further use of the apparatus the gas will be automatically removed by the flowing water, resulting in the circuit being again closed through the trap fluid. It is obvious that in the operation of any apparatus wherein it is desirable to automatically open a circuit through electro-chemical reaction, this method may be employed.

Instead of using the form of electrode shown in Figure 5, I may use such a construction as that shown in Figure 4, in which is shown a modified form of trap, partly broken away. In this case the gas resulting from the chemical reaction rises in the chamber 12 surrounding the lower free end of the electrode 7, forcing the trap fluid away from contact with the electrode and automatically opening the circuit.

In Figure 2 I have shown a modified form of apparatus, partly in section, in which the waste is employed as the active fluid, or electrolyte, in a voltaic cell, the current generated thereby being employed, through a relay 30, to close an independent circuit 50, which controls the operation of the valve 4. Voltaic couples, 2 and 20, are shown as contacting with the sealing fluid. The trap may form an integral part of the urinal body 1 and is provided with the cover 81, which may be in the form of a strainer, and the partition 70, which prevents gas escaping through the apparatus. Means are provided at 29 for passing the circuit 19 through the discharge pipe 10.

In Figure 3, I have shown my method as applied in the operation of automatically flushing a closet bowl, which is shown partly in section. The voltaic couples 2 and 20, in modified form, are placed to contact with the water forming the seal of the bowl, the other parts being essentially as heretofore described. I have also shown a roll of toilet paper 15, to which may be applied, or have incorporated therein, a chemical which is innocuous to the user, but which will dissolve in the water, making of it a better electrolyte, thereby increasing the current flowing in the relay or other circuit. This fluid may also form a resistance in the external path of a circuit, in which case the use of a relay would not be necessary.

Fluids in many conditions offer various resistances to the passage of an electric current and with my method the supply, or discharge, of all such fluids may be regulated by the employment of apparatus best suited for the particular purpose without departing from the spirit of my invention.

In waste receiving receptacles such as urinals and water closets, the temperature of the waste is considerably higher than that of the normal sealing fluid and this condition of the waste, either alone or combined

with the chemical effect, may be employed to advantage to control or to increase the effectiveness of the apparatus.

There are many forms of apparatus in which my method may be employed. In many cases where chemical reactions are taking place, it is desirable to discharge the fluid, or add new fluid, after a certain amount of chemical reaction has taken place. This would be particularly true where replenishing fluid is required in storage, or other batteries, or for electrolytic rectifiers and the like. In all these cases the controlling mechanisms may be made to operate in conformity with the conductivity of the fluid. My method may also be applied in the operation of pumping, or in apparatus having for its object the caring for sewage, factory wastes, or for regulating the supply, or discharge, of various fluids in various conditions.

What I claim as my invention is:

1. The method of automatically starting intermittently operated mechanisms which 25 consists in varying the chemical character of a fluid in the path of a normally-charged closed circuit which controls said mechanisms and using the varying resistance of said fluid to control the current in said 30 closed circuit to thereby actuate said mechanisms.

2. The method of regulating the delivery of a fluid which consists in using the fluid as the internal resistance in the path of a 35 circuit and using the varying resistance of the fluid to control the actuating mechanisms.

3. The method of automatically stopping an electrically controlled fluid supply by 40 varying the conductivity of a fluid which forms a medium in a path which is common to both the fluid supply and the current in a supply controlling circuit.

4. The method of automatically stopping an electrically controlled fluid supply by introducing said fluid supply into a gap in a supply-controlling circuit which is bridged by a fluid of another conductivity.

5. The method of automatically regulating a flow of fluid by fluctuations in a circuit which consists in varying the conductivity of a fluid interposed in a gap in a supply controlling circuit and utilizing the fluctuations of current thereby produced to 55 govern the operation of the supply regulating mechanisms.

6. The method of automatically regulating a flow of fluid by fluctuations in a circuit which consists in varying the conductivity of a fluid which bridges said circuit at a point which is in the path of flow of said fluid and utilizing the variations in the conductivity of said circuit to govern the operation of the supply regulating mechanisms.

7. The method of automatically regulating a flow of fluid by fluctuations in a supply-controlling circuit which consists in varying the conductivity of a fluid which forms a medium in a path which is common to both the fluid supply and the current in said circuit and utilizing the fluctuations of current thereby produced to govern the operation of the supply controlling mechanisms. 75

8. The method of automatically regulating a flow of fluid by fluctuations in a circuit which consists in varying the conductivity of a fluid which forms a medium in the path of the fluid supply and utilizing the variations in conductivity thereby produced to govern the operation of the supply regulating mechanisms. 80

9. The method of automatically regulating a flow of fluid by variations in the conductivity of a fluid which is interposed in a gap in a supply controlling circuit at an intersection which is common to the flow of fluid. 85

10. The method of automatically stopping an electrically controlled fluid supply by substituting the said fluid supply for a more conductive fluid which is in the path of the controlling current. 90

11. The method of securing an automatic flushing action which consists in producing an increased flow of electric current by increasing the conductivity of the circuit through the deposit of a waste in a body of fluid which is included in said circuit 100 and in applying said increased current flow to replace said fluid by a less conductive fluid to thereby reduce the flow of electric current and thus cut off the fluid flow. 95

12. The method of controlling the operation of flushing mechanisms for urinals, water closets, and the like, which consists in using the waste as a conductor to close a circuit controlling the operation of the flushing mechanism and using the flushing fluid as a resistance to reduce the conductivity of said circuit. 105

13. The method of automatically regulating a flow of fluid the path of which is intersected by a supply controlling circuit 115 which consists in utilizing fluctuations in said circuit due to variations in the conductivity of a fluid medium included in said circuit to govern the operation of the supply regulating mechanisms. 120

14. The method of automatically stopping an electrically controlled fluid supply by substituting the said fluid supply for a more conductive fluid which forms a resistance in the controlling circuit during the operation 125 of the apparatus.

Signed at Seattle, Washington, this 13th day of July, 1916.

EDGAR EARLE LITTLEFIELD.
